CONTROLLER FOR DRIVING MECHANISM

Application filed January 14, 1930. Serial No. 420,789.

This invention relates to improvements in controlling devices for driving mechanism, such for instance as the shipper of a loom, and it is the general object of the invention to provide a simple yielding lock effective to cause quick release of the driving mechanism in an efficient manner.

While the invention is not limited to looms yet it is particularly usable on certain types of looms which employ the so-called forward pull shipper handle. In looms of this type it has been customary heretofore to employ a jointed connection operating somewhat after the manner of toggle joints, being so constructed as to hold the driving and driven elements together by means of a yieldable lock. Because of this arrangement stopping of the machine brings about first a straightening of the toggle which temporarily increases the pressure between the driving and driven surfaces, this pressure, however, being relieved as soon as the jointed connections move to stopping position. There is, however, an interval at the beginning of the knocking-off stroke when the pressure is increased rather than relieved. It is an important object of my present invention to provide mechanism of this general class but so arranged that the toggle lock will become immediately effective to lessen pressure between the driving and driven surfaces without the objectionable delay due to the increase mentioned.

It is a further object of my present invention to provide a shipping or control lever with a pivoted member having inclined surfaces which cooperate with a fixed operating or stop element such as a stud to move the member to lever locking position when power is to be transmitted, and effective by a slight pressure on the lever to bring about unlocking when the driving members are to be disconnected.

With these and other objects in view which will appear as the description proceeds, my invention resides in the combination and arrangement of parts hereinafter described and set forth in the claims.

In the accompanying drawings, wherein a

convenient embodiment of my invention is set forth,

Fig. 1 shows a side elevation of a portion of a loom having my invention applied thereto, the parts being in normal running position, 55

Fig. 2 is a top plan view taken in the direction of arrow 2, Fig. 1,

Fig. 3 is a fragmentary view similar to Fig. 1 on an enlarged scale showing certain parts 60 thereof on an enlarged scale and with the parts in stopping position, and

Fig. 4 is a view similar to Fig. 3 but with the parts in driving position.

Referring to Figs. 1 and 2, I have shown a 65 machine frame such for instance as a loom-side 10 which supports a driving shaft 11. The latter has secured thereto a gear 12 having a friction surface 13 to cooperate with a corresponding surface 14 provided on the driving gear 15 loose on the shaft. A bracket 16 secured to the loomside has pivoted thereto a rocking lever 17 operatively connected to the gear 15. The latter may be rotated in any approved manner as by an electric motor pinion not shown and is capable of sliding into driving engagement with the surface 13 under action of the lever 17. A small bell crank lever 18 is pivoted to the bracket 16 and has a forwardly extending rod 19 which 70 when moved forwardly or to the left operates to disengage the driving surfaces. 75

The forward portion of the loom is provided with a shipper shaft 20 to which is secured a shipper lever or handle 21 pivotally connected as at 22 to the forward end of said rod 19. The shipper handle has a depending arm 23 carrying the pivot 22 and adapted for engagement with a fixed stop 24. 80

In order to illustrate the manner of actuating the shipper handle so as to effect stopping of the machine automatically I have set forth a lay 25 from the lower forward portion of which projects a dagger 26. The latter is adapted for engagement with a knock-off lever 27 having a portion extending in front of the shipper lever. Under certain conditions, such for instance as failure of the shuttle to be properly boxed or breakage of the filling laid by the shuttle, the dagger 90 95 100

26 will be moved into position to engage the lever as the lay moves forwardly or to the left, thereby causing the lever 27 to move the shipper handle from the left position shown in Fig. 1 to the right or in a clockwise direction around the shipper shaft 20. When this motion on the part of the shipper handle takes place the rod 19 will be moved forwardly, thereby moving the driving gear 15 away from the friction surface 12.

10 The matter thus far described is of common construction in looms more particularly of the silk or worsted type and forms no part of my present invention, except as hereinabove described.

15 In carrying my invention into effect I provide the lower part of arm 23 with a stud 30 around which a control member 31 may swing as a pivot. The member is provided with a 20 stop ear 32 adapted to engage the stud 22 to limit angular movement of the member 31 in a counter-clockwise direction with respect to the shipper handle. A pivot 33 is provided on the member for the left hand end of a push 25 rod 34 having a collar 35 to receive the forward thrust of a compression spring 36. The rod passes through an adjustable but normally fixed guide bracket 37.

30 Lying between the stud 30 and the pivot 33 is a slot having substantially parallel sides which are oblique with respect to a line joining the centers of the stud 30 and pivot 33. An operating or stop element 38 which is normally fixed and mounted on a stand 39, which 35 can be adjusted as to position as set forth, is positioned to enter the slot. The left side of the slot has a surface 40 while the opposite side of the slot has a preferably parallel surface 41, the slot terminating at the upper end thereof in a surface 42 which may engage the element 38 to limit angular movement of the control member 31.

35 When the driving and driven members are disconnected, or in stopped position, the parts will be in the position shown in Fig. 3 with the operating element or stop 38 out of the slot but positioned to engage surface 40. As the shipper handle is pulled forwardly the arm 23 and control member 31 will move as a 40 unit without relative angular motion, this position or condition of balance being maintained by the spring 36. As soon as the surface 40 engages the fixed operating element 38, however, the member 31 will begin to rotate about the stud 30. Up to this time the spring has had control over the shipper lever to determine the position of the latter, but as the pivot 33 starts to move downwardly the force exerted by the spring will more 45 nearly approach the center of the stud 30.

50 As the shipper handle continues to be moved forwardly or to the left the angular relation between the surfaces 40 and 41 and the arm 23 and also the aforesaid line changes. 55 As soon as pivot 33 passes below this line of

force the spring 36 will start to expand, causing surface 41 to slide over the operating element 38. As the pivot 33 moves down the line of force will pass below the stud 30. A time will come in this movement of the member 31 when the force of the spring will be balanced and arrested by our opposing force developed by contact between surface 41 and the stop 38. The stop surface 42 may engage the stud 38 to limit movement of the control member, 75 but I find in experience that the surface 42 is not always in engagement with the stud 38 during loom running. When in this position spring 36 will act as a yielding lock to maintain the several parts in the balanced 80 relation shown in Fig. 4, which corresponds to the running position.

85 The degree of lock may be varied by changing the location of the operating member 38, such a change altering also the friction between the stud and surface 41. When the stud 38 is raised the lock becomes more sensitive, while if it be lowered the lock is more secure. The amount of motion of the shipper 90 handle or lever is controlled by the horizontal position of the stud 38.

95 When it is desired to stop the machine the operator will give the upper end of the shipper handle a slight rearward push, or to the right as viewed in Fig. 1. It should be noted that the surface 41 is oblique with respect to the line passing from the center of the stud 30 through the guide and for this reason pressure on the shipper handle as described will cause said surface 41 to move over the 100 fixed stud or element 38. Under these conditions the motion of the operating member 31 is a reverse of that previously described and as the shipper handle continues to move to the right the surface 41 will become more and more inclined with respect to a vertical line passing through the operating element. The accompanying angular movement of control member 31 causes the line of force exerted by the pressure element or spring 36 to approach stud 30. As the pivot 33 rises it will 105 assume a position beyond the opposing forces which are unable to further restrain the spring 36, whereupon the latter will swing the operating member around the stud 30 to move the same to the position shown in Fig. 3.

110 Member 31 will continue its motion until the ear 32 engages the stud 22, after which the pressure of the spring will be brought to bear against the shipper handle tending to move the same in a clockwise direction so as to effect forward movement of the rod 19.

115 From the foregoing it will be seen that I have provided a simple means whereby a slight rearward movement of the shipper handle will disturb the existing condition of balance of forces and thereby permit the spring 36 to start the shipper lever on its movement toward stopping position. It will be noted that this action takes place with- 120

out a temporary tightening of the friction surfaces 13 and 14 as has been the case in existing constructions of this type. It will further be seen that the spring 36 which acts to hold the shipper lever in normal running position is the means which also moves the lever to stopping position and that the line of force exerted by this spring, not normally being directed to one side of the pivot 30, creates a balanced condition with the shipper lever either in running or stopping position. It will also be seen that the inclined surface 41 plays an important part in the movement of the shipper lever to stopping position without causing the previously referred to temporary increase in pressure between the driving friction surfaces.

Having thus described my invention it will be seen that changes and modifications may be made therein by those skilled in the art without departing from the spirit and scope of the invention and I do not wish to be limited to the details herein disclosed, but what I claim is:

1. In a control device for driving mechanism, a shipper member to be normally in running position and movable to stopping position, a device exerting a force in the direction in which the shipper member moves when moving from running to stopping position, a fixed stop exerting an opposing force to overpower the force exerted by the device and retain the member in running position, an element pivoted to the member and receiving the thrust of the force exerted by the device, and a surface on the element, said first named force holding the surface against the stop and said surface being inclined relatively to a line joining the pivot of the element and the point of application of the first named force to the element and away from the pivot of the element, the operator when giving the member a slight movement toward stopping position thereby adding a small force to the first force so that these two forces overcome the second force and move the member to stopping position.

2. In a control device for driving mechanism, a shipper lever movable about a fixed center, driving means controlled thereby, a control member pivoted to the shipper lever, a yielding pressure element, a pivotal connection between the pressure element and the control member, a guide for the pressure element through which the latter slides as the control member moves, a fixed operating element, and means on the control member defining a surface cooperating with the element and oblique with respect to a line joining the pivot of the pressure element and the pivot of the control member, the pressure member exerting its force along a line passing to one side of the pivot of the control member under normal running conditions, the pressure member yielding as the shipper lever starts

its movement toward stopping position because of the cooperation of the inclined surface and the operating element.

3. In a control mechanism for driving devices, a pivoted shipper lever, a control device pivotally mounted on the shipper lever, a pivotal connection between the control member and the shipper lever, a fixed stop, a pressure element attached to the control member and exerting a force on the latter which passes to one side of the pivotal connection, and an inclined surface formed on the control member and held against the stop by the pressure element under normal running conditions, said inclined surface and stop being so related that a slight movement of the shipper lever from running toward stopping position will effect pivotal movement of the control member to cause the line of force exerted by the pressure element to approach the pivotal connection, said pressure element thereafter moving the control member and shipper lever to stopping position and causing the inclined surface to slide along the fixed stop.

4. In a control mechanism for driving devices, a pivoted shipper lever, a control device pivotally mounted on the shipper lever, a pivotal connection between the control member and the shipper lever, a fixed stop, a pressure element acting on the control member and exerting thereon a force which passes to one side of the pivotal connection, stopping surfaces carried by the control member and held in engagement with the fixed stop under normal running conditions by the pressure element, said surfaces including a portion inclined with respect to a line joining the pivotal connection and the point at which the force of the pressure element is exerted on the control member, the shipper lever when moving slightly from running toward stopping position causing movement of the control member due to coaction of the inclined surface of the fixed stop to cause the line of force exerted by the pressure element to approach the pivotal connection, thereby causing said inclined surface to slide along the fixed stop under action of the pressure element and the latter moving the shipper lever toward the stopping position.

5. In a control mechanism for driving devices, a pivoted shipper lever, a control device pivotally mounted on the shipper lever, a pivotal connection between the control member and the shipper lever, a fixed stop, an inclined holding surface formed on the control member, a pressure element exerting a force on the control member and holding the surface against the fixed stop to create a condition of balance with the shipper lever in running position, said surface being inclined with respect to a line joining the pivotal connection and the point at which the force of the pressure element is exerted on

- the member, said force being directed in a direction to one side of the pivotal connection, said stop and inclined surface being so related that a slight movement of the shipper lever from running toward stopping position causes a movement of the inclined surface along the stop to produce pivotal movement of the member and cause the line of force exerted by the pressure element to approach the pivotal connection, thereby destroying the previously referred to balance and causing the inclined surface to slide along the stop and effect movement of the shipper lever in a direction toward stopping position.
6. In a control mechanism for driving devices, a pivoted shipper lever, a control device pivotally mounted on the shipper lever, a pivotal connection between the control member and the shipper lever, a fixed stop, a pressure element to exert a force on the control member, means defining a pair of substantially parallel stop engaging surfaces which are oblique with respect to a line joining the pivotal connection and the point of application of the force of the pressure element, the stop under normal running conditions engaging one of said surfaces to hold the control member so that the line of force of the pressure element passes to one side of the pivotal connection and holds the control member and shipper lever in driving relationship and in a state of balance, movement of the shipper handle toward stopping position causing relative movement between the stop and one of the inclined surfaces to rock the control member against the action of the pressure element and move the line of force of the latter toward the pivotal connection, said element thereafter moving the control member and shipper lever to stopping position with the member and lever in a different relation corresponding to stopping position, said shipper lever when being returned to running position from the stopping position causing engagement of the other of said surfaces with the stop to effect return of the control member to a position relative to the lever which corresponds to running position, this returning movement of the control member causing the line of force exerted by the pressure element to pass from one side to the other side of the pivotal connection.
- 55 In testimony whereof I have hereunto affixed my signature.

ELBRIDGE R. HOLMES.
